C. E. NYSTRUM.
CUSPIDOR.

APPLICATION FILED MAY 14, 1917.

1,239,716.

Patented Sept. 11, 1917.

UNITED STATES PATENT OFFICE.

CONRAD E. NYSTRUM, OF MEDFORD, WISCONSIN, ASSIGNOR OF ONE-FOURTH TO
EUGENE M. WHITE, OF MEDFORD, WISCONSIN.

CUSPIDOR.

1,239,716.

Specification of Letters Patent. Patented Sept. 11, 1917.

Application filed May 14, 1917. Serial No. 168,419.

To all whom it may concern:

Be it known that I, CONRAD E. NYSTRUM, a citizen of the United States, residing at Medford, in the county of Taylor and State 5 of Wisconsin, have invented certain new and useful Improvements in Cuspidors, of which the following is a specification, reference being had to the accompanying drawings.

This invention relates to certain improvements in cuspidors, and it is an object of the invention to provide a novel and improved device including a receptacle folded from a single blank or sheet of material and wherein the folded portions of the device 10 are effectively maintained in operative relation.

It is also an object of the invention to provide a novel and improved cuspidor wherein is embodied a receptacle produced from material inflammable at a relatively high temperature whereby said member and its contents may be incinerated after being in use, and wherein said receptacle is adapted to be applied within a rigid member.

25 The invention consists in the details of construction and in the combination and arrangement of the several parts of my improved cuspidor whereby certain important advantages are attained and the device is 30 rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings; wherein—

40 Figure 1 is a vertical sectional view taken through a cuspidor constructed in accordance with an embodiment of my invention and wherein the receptacle is seated within its coacting rigid member;

45 Fig. 2 is a view in side elevation of my improved receptacle as herein embodied, with certain of the parts indicated by dotted lines;

Fig. 3 is a view in top plan of my improved receptacle as herein disclosed;

50 Fig. 4 is a fragmentary sectional view taken substantially on the line 4—4 of Fig. 2;

Fig. 5 is a fragmentary sectional view

taken substantially on the line 5—5 of Fig. 55 2; and

Fig. 6 is a view in plan of a blank from which my improved receptacle is formed.

As disclosed particularly in Fig. 1, C denotes a container or rigid member in which 60 is adapted to be seated the removable receptacle or receiving member R. The base portion of the container or member C is defined by an outstanding flange 1^a, relatively broad, and which serves effectually to prevent upsetting of the member C. I also find it of advantage and especially from an esthetic view point to employ a mat 1^b of rubber or other material overlying the flange 1^a and suitably secured thereto. I also find it desirable to have the mat 1^b of such size as to 65 extend a predetermined distance beyond the free margins of the flange 1^a.

The receptacle or receiving member is preferably formed of material inflammable at 75 a relatively high temperature, so that after said receptacle or receiving member R has been in use, said receptacle or member together with its contents may be incinerated.

My improved receptacle or receiving member as herein embodied is formed from a single blank of material, such as cardboard or the like, and said blank is of the form particularly illustrated in Fig. 6 of the drawings. As disclosed in Fig. 6, it is to be 85 noted that the central portion of the blank is provided with the scored lines *a* arranged substantially in the form of a Roman cross, whereby the bottom 1 and the sides 2 of the receptacle or member R are defined. The 90 outer ends of two opposed sides 2 are provided with the tongues 3, each of said tongues being intersected by a notch 4, for a purpose to be hereinafter more particularly referred to. The blank intermediate 95 the scored lines *a* of adjacent sides 2 have their outer edges in the form of an isosceles triangle, as indicated at 5, with the apex thereof disposed outwardly. The portion of the blank intermediate the scored lines of 100 adjacent sides 2 are intersected by the scored lines *b* extending from the apices of said portions to the adjacent or intersecting point of the adjacent scored lines *a*. When the sides 2 are folded upwardly the intermediate portions 5 of the blank are folded along the scored lines *b* so that the material at opposite sides of the scored lines *b* will 105

be in overlying relation. The folded portions 5 are then flexed on the lines *a* to overlie the outer faces of the sides 2 provided with the flaps or tongues 3, as indicated in Fig. 2.

The outer ends of the second pair of sides 2 and the portions 5 intermediate said second sides 2 and the adjacent scored lines *b* are provided with the relatively wide flaps 6, which are adapted to be folded inwardly and downwardly within the receptacle or member R on the scored lines *c*, to afford a top having its central portion provided with a restricted opening 7. The portions of the flaps 6 adjacent the outer corners of the sides 2 are provided with inwardly converging scored lines *d* arranged in series of three and which are adapted to be folded inwardly at the corners of the receptacle. The portions 20 of the flap 6 in alignment with the adjacent sides 2 are each provided at its outer margin with the inwardly converging slits 8 adapted to be interlocked, as indicated at 9 in Fig. 3, with the two outer plies of the folded portions as afforded by the scored lines *d*.

After the blank has been folded in order to produce the receptacle or member R, a handle H of wire or the like is engaged through the overlying portions 5 of the adjacent sides 2. The handle member H facilitates the removal of the receptacle or member R from within the container or rigid member 1. It is also to be understood that a suitable cover member is adapted to be applied over the open end of the receptacle or member R when the same is transported, in order to maintain the same sanitary.

From the foregoing description, it is thought to be obvious that a cuspidor constructed in accordance with my invention is of an extremely simple and comparatively inexpensive nature and is particularly well adapted for use by reason of the convenience and facility with which it may be assembled, and it will also be obvious that my invention is susceptible of some change and modifica-

tion without material departure from the principles and spirit thereof and for this reason I do not wish to be understood as limiting myself to the precise arrangement and formation of the several parts herein shown in carrying out my invention in practice, except as hereinafter claimed.

I claim:

1. A device of the character described comprising a receptacle formed from a single blank of material folded on lines similar to a Roman cross to afford a bottom and sides, the portions of the blank intermediate the sides being folded to overlie adjacent sides, the outer end portions of the remaining sides being provided with flaps, said flaps being extended along one of the folds of each of the intermediate portions, said flaps being extended inwardly and downwardly of the receptacle to afford a top provided with a restricted opening, the lower portions of adjacent flaps interlocking.

2. A device of the character described comprising a receptacle formed from a single blank of material folded on lines similar to a Roman cross to afford a bottom and sides, the portions of the blank intermediate the sides being folded to overlie adjacent sides, the outer end portions of the remaining sides being provided with flaps, said flaps being extended along one of the folds of each of the intermediate portions, said flaps being extended inwardly and downwardly of the receptacle to afford a top provided with a restricted opening, the lower portions of certain of the flaps being provided with slits to interlock with the lower portions of the remainder flaps.

In testimony whereof I hereunto affix my signature in the presence of two witnesses.

CONRAD E. NYSTRUM.
